Application April 19, 1935, Serial No. 17,240

4 Claims. (Cl. 200—122)

Our present invention relates to a flashing device for incandescent lamps and comprises an improved combined lamp and flasher element therefor that is rapid in operation and economical to manufacture. The invention includes also a flasher device that may be used for flashing one or a plurality of lamps.

In U. S. Patent No. 1,998,823, dated April 23, 1935, we have disclosed and claimed a combined flasher and incandescent lamp which is particularly suitable for use as a flashing stop light for automobiles. The device of the present invention, while having certain features in common with that of our co-pending application, differs therefrom in that it is relatively simpler and cheaper to manufacture, in that it may be positioned entirely within a lamp bulb and in that the expansible wire controlling the operation of the flasher is heated by radiation rather than by the passage of electric current therethrough. The present device, like that of our co-pending application, operates by shunting a resistance in series with a lamp filament and thus avoids sparking incident to devices which operate by opening and closing a circuit.

For an understanding of the invention reference may be had to the accompanying drawings of which—

Fig. 1 is a horizontal sectional view taken along the line 1—1 of Fig. 2 of a combined incandescent lamp and flasher element therefor in which the flasher element is located within an annular member mounted on the base of the lamp.

Fig. 2 is a vertical section along the line 2—2 of Fig. 1.

Fig. 2a is a detail view in perspective of the cover for the annular member of Figs. 1 and 2.

Fig. 3 is a vertical sectional view of a combined incandescent lamp and flasher element therefor in which the flasher element is located within the lamp bulb, and

Fig. 4 is a vertical sectional view of a separate flasher for use in connection with one or more external incandescent lamps.

The construction illustrated in Figs. 1, 2 and 2a is that preferred for small lamps, such as automobile stop lights. In this construction the flasher element is carried within an annular conducting member 2 mounted on the base 4 of a lamp bulb 6. The flasher element includes a pair of contacts 8 and 10, a resilient member 12 having one end mounted on the vertical wall of the annular member 2 and carrying on its movable end the contact 10, an expansible wire 14 secured at one end to the container wall and at

its other end to the movable end of the resilient member 12, and a resistance coil 16 electrically connected between the annular container 2 and the incandescent filament 18 of the lamp. Resistance 16 serves as a heater for the expansible wire 14 and also as a series resistance for the incandescent filament 18. Filament 18 is connected at one end by means of a lead wire 20 to one terminal 22 of the base 4 and at its other end by means of a lead wire 24 to the resistance 16. Lead wire 24 at the point of emergence into the annular chamber within member 2 is electrically insulated from the base 4 and container 2 by means of an insulating strip 26. Contact 8 is carried by lead wire 24 and is positioned to be engaged by contact 10 when wire 14 expands sufficiently under the influence of heat radiated from resistance coil 16 to permit movement of the resilient member 12. Member 12 is of spring metal and preferably is curved about its longitudinal axis, convex toward the wire 14, to insure hinge-like movement about the point of contact with the container wall. The spring member 12 tends to move against the tension of wire 14 into contact closing position.

Container 2 is preferably soldered to the base 4 to insure good electrical contact therewith and to insure continued alignment of contacts 8 and 10. A suitable cover for the annular container 2 is shown in Fig. 2a, as comprising an upper horizontal wall portion 27 in the form of a ring split into halves at 28 and 29, and a vertical wall section 30 integral with the horizontal wall section and in the form of a cylinder split at 29. The walls of the cover are preferably of metal and are thin enough to permit the side wall to bend about the point 28 when the parts of the cover are spread to pass around the lower portion of the bulb 6. When the cover has been brought into position over the container 2 the spread apart portions are brought into contact and soldered or welded together.

After assembly of the various parts within the container, but before the cover is applied, adjustment of the flasher operation may readily be effected by varying the tension of wire 14 while current is passed through the device. When proper operation is obtained the end of the wire is welded or soldered to the container wall and the cover positioned.

When the base 4, which in the particular embodiment of the invention illustrated, is of the bayonet type, is plugged into a socket and the normal operating potential difference is applied across the terminal 22 and outer conducting wall 55

of the base, current flows through conductor 20, filament 18, conductor 24 and resistance 16 back to the container and base. Thus resistance 16 will be connected in series with the filament 5 across the lamp terminal and will limit the current through the filament to a value insufficient for incandescence. Heat, radiated from resistance 16 during the passage of this current therethrough, causes wire 14 to expand sufficiently to 10 permit spring member 12 to move to contact closing position where resistance 16 is shunted by member 12 and the current through the filament consequently increased and the temperature thereof raised to that of incandescence. The 15 shunting of resistance 16 reduces the heat radiated to wire 14 and permits it to cool and contract. The contraction of the wire draws spring 12 back to its initial position where contacts 8 and 10 are out of engagement. This cycle of 20 alternate dimming or extinguishing and lighting of the lamp continues as long as potential difference is applied across the terminal of the base.

By utilizing a fine wire with its corresponding small heat capacity, a rapidity of operation, is 25 obtained which could not be obtained with for example the bi-metallic type of heat responsive elements. Bi-metallic elements have a relatively larger metallic body and, depending as they do upon distortion for their controlling effect, are 30 necessarily slow acting.

Where small flashing lamps are desired, the above described construction, where the flasher parts are located in the annular container carried on the base of the lamp is preferred. For larger 35 lamps, a relatively simpler and preferred embodiment of the invention is that illustrated in Fig. 3 wherein the flasher elements are incorporated within the lamp bulb.

In the construction illustrated in Fig. 3, the 40 lamp bulb 32 is provided with three conducting support rods 33, 34, and 35 mounted in the press of the bulb. Support 35 carries the fixed contact 36 of the device. The filament 38 of the lamp is connected across supports 33 and 35 and the resistance coil 40 is connected across supports 34 and 35. Spring member 42 carrying the movable contact 44 on one end thereof is secured at its other end to support 34. Expansible wire 46 is secured between the support 34 and the contact 45 carrying end of spring 42 so as to prevent, when cold, movement of spring member 42 to contact closing position. Support 33 is electrically connected by lead 48 with a terminal 50 of the base 52 of the lamp and support 34 is electrically connected by means of lead 54 to the other terminal 56 of the base. The circuit of the device of Fig. 3 and the operation thereof will be clear from the description given in connection with the embodiment of the invention illustrated in Figs. 1 and 2. 50 When the base is inserted into a socket and a potential difference applied across the terminals 50 and 56, current, insufficient to cause incandescence of the filament, flows through the filament and resistance in series; the circuit being from 55 terminal 56 through lead 54, support 34, resistance 40, support 35, filament 38, support 33, and lead 48 to terminal 50. Expansion of wire 46 under the influence of the heat radiated from resistance 40 permits spring 42 to bring contact 44 into engagement with contact 36 whereupon resistance 40 is shunted by the spring member and substantially the full lamp voltage is impressed across the filament until the subsequent contraction of wire 46 causes reopening of the 60 contacts. As in the device of Figs. 1 and 2 the

75 fineness of the expansible wire will insure relatively rapid operation of the flasher.

If the surface of the resistance coil is electrically insulated, as for example by spraying with ceramic or other suitable insulating material, the expansible wire may be positioned within the coil along the axis thereof as indicated in Fig. 3.

In Fig. 4 a flasher suitable for operating any number of lamps connected in series therewith is illustrated. This flasher differs from the combined flasher and lamp of Fig. 3 substantially only in the omission of the incandescent filament and the additional conducting support therefor. As shown, the flasher comprises a bulb 58 mounted in a base 60 having terminals 62 and 64, a pair of conducting supports 66 and 68 electrically connected with terminals 62 and 64 respectively, a resistance coil 70 connected across the supports 66 and 68, a spring member 72 mounted on support 66 and carrying a contact 74 on the remote end thereof adapted to engage the fixed contact 76 on support 68 and expansible wire 78 connected to support 66 and the contact carrying end of spring member 72.

In operation current flows through the resistance 70 until expansion of wire 78 under influence of the heat radiated from resistance 70, permits spring 72 to bring contact 74 into engagement with contact 76 whereupon the resistance 70 is shunted by spring member 72 until the subsequent contraction of wire 78 causes reopening of the contacts. Thus a lamp connected in series with the terminals of the flasher of Fig. 4 would have its filament current periodically varied as the series resistance 70 was alternately cut in and out of the circuit by the successive opening and closing of the flasher contacts.

In Figs. 3 and 4 the spring members carrying the movable contacts have been indicated in the drawings as being flat leaf springs. It will be understood however that the construction illustrated in Figs. 1 and 2, wherein curvature along the longitudinal axis imparts additional stiffness to the spring member may be employed in each of the embodiments illustrated in Figs. 3 and 4 if desired.

In the case of the constructions illustrated in Figs. 3 and 4, adjustment of the tension of the expansible wire is effected prior to the sealing 5 of the press carrying the conducting supports into the bulb, preferably while a potential difference is applied across the supports between which the heater is connected.

Our invention has now been described with 5 reference to the particular embodiments illustrated in the drawings. In each embodiment, the elements of the relatively quick acting and simple flasher include an expansible, relatively fine, wire which, when cold, prevents the shunting of a resistance and which, when subjected to the heat radiated from that resistance expands and permits shunting of the resistance. In each of the embodiments illustrated in Figs. 1, 2 and 3 the combined flasher and lamp may be inserted within a standard socket to operate upon application of normal potential difference across the terminals thereof. In each embodiment sparking incident to the opening and closing of a circuit is avoided by the provision of a continuously closed circuit. It will be understood that the invention in its broadest aspect is not limited to the particular constructions illustrated as various changes might be made therein 75

without departing from the scope of the invention as defined in the appended claims.

We claim:

- 5 1. The combination in a flashing device of an electrical resistance, means for shunting said resistance, said means including a resilient member biased toward shunting position and an expansible wire controlling said last mentioned means and positioned to be influenced by heat radiated 10 from said resistance upon passage of electrical current therethrough, said wire when cold mechanically preventing movement of said resilient member to shunting position.
- 15 2. The combination in a flashing device of a bulb, a base on the bulb having a pair of terminals, a pair of conducting supports mounted in the press of the bulb and electrically connected to said terminals, an electrical resistance connected between said supports, a resilient conducting member mounted on one of said supports and extending at an angle therefrom toward the other of said supports, a contact carried on the movable end of said resilient member, a contact on said other one of said conducting supports 20 positioned to be engaged by said first contact and an expansible wire secured at one end to the support carrying said member and at its other end to the movable end of said member, said wire being positioned to be influenced by heat 25 radiated from said resistance and being tensioned to prevent movement of the end of said member into contact closing position when the wire is
- 30 cold and to permit such movement when expanded by heating whereby, when a potential difference is impressed across said terminals said resistance is intermittently shunted by said resilient member. 5
3. The combination in a flashing device of an electrical resistance, means including a strip of spring metal having one end fixed against movement, for shunting said resistance and an expansible wire mechanically preventing, when 10 cold, movement of said strip to shunting position, said wire being positioned to be influenced by heat radiated from said resistance upon passage of current therethrough, said wire having one end fixed and its other end secured to the movable end of said strip and said strip for a substantial length thereof being of a curved cross section, convex toward said wire, whereby said strip upon contraction and expansion of said wire moves substantially throughout its length. 15 20
4. The combination in a flashing device of an electrical circuit including an electrical resistance and a pair of contacts adapted when closed to shunt said resistance, means including a resilient member constantly tending to close said contacts, and an expansible wire positioned to be influenced by heat radiated from said resistance upon passage of current therethrough, said wire when cold mechanically preventing closure of said contacts 25 by said resilient member. 25 30
